PROPORTIONER FOR TREATING MATERIAL

Harvey C. Waugh, Hammond, Ind., assignor to
American Water Softener Company, Philadelphia, Pa., a corporation of New Jersey

Application February 25, 1930, Serial No. 431,228

4 Claims. (Cl. 210—17)

My invention relates to a proportioner adapted to control the feed of wet or dry materials for treating purposes to wet or dry material to be treated.

5 A purpose of my invention is to use the operation of a meter which is measuring one flow to make successive electric contacts and electromagnetically to proportionately feed a liquid or solid treating medium.

10 A further purpose is to utilize electric impulses caused by a meter which measures the flow of a liquid to measure out and discharge into the liquid a solid or liquid treating material.

15 A further purpose is to apply electromagnetic impulses controlled by a meter to the operation of any of a large variety of devices for proportionately feeding a treating liquid or solid material.

20 A further purpose is to provide novel mechanism for adjusting the relation between movement of the meter measuring one flow and a delivering device controlling the feed of a material to be mixed with this flow.

25 A further purpose is to operate a feed of treating material, liquid or solid, by solenoidal means controlled by contacts effected at intervals by the meter.

30 A further purpose is to form quick make and break contacts through the operating mechanism of a meter and to electromagnetically utilize current through these contacts for the feeding of treating material into the liquid measured.

35 A further purpose is to provide an adjustment of the amount of feed of an electromagnetically-operated liquid-treating apparatus.

40 A further purpose is to close an electric circuit by measuring movement of a closed meter subject to pressure, to use the impulses from the current flowing to cause feeding of a treating material to the liquid metered, and to adjust the extent of the feeding effected.

Further purposes will appear in the specification and in the claims.

45 I have preferred to show a few forms only among the many in which my invention may appear and have selected the forms with special reference to their illustration of the principles involved.

Figure 1 is a section upon line 1—1 of Figure 2 50 but with added structure.

Figure 2 is a top plan view of part of the structure seen in Figure 1.

Figure 3 is an enlarged fragmentary section corresponding to Figure 1 but omitting a gear 55 seen in Figure 1.

Figure 4 is a section of the structure in Figure 3 taken upon line 4—4.

In the drawing similar numerals indicate like parts.

Many liquids are treated by solid or liquid addition for corrective purposes, the addition being proportionate to the quantity of base liquid flowing. This need exists in many lines, such, for example, as in the treatment of water for boiler or drinking purposes and in all sorts of 10 industries in which a change, usually chemical, must be effected.

I recognize that the invention is applicable in a great variety of locations and through a great variety of distributing or other devices. 15

The largest immediate use for an invention of this character at present exists in the treatment of raw water to which a solid or liquid chemical is added at a rate proportional to the rate of flow of this stream. 20

In Figure 1 the main flow of liquid to be treated takes place through pipes, not shown, and a meter whose contact mechanism only is there shown.

The meter may be of any suitable character 25 having movable parts.

The meter operates a contact mechanism shown in Figure 1 as a pair of ratchet wheels 22 and 23 upon which ride fingers 24 and 25. These fingers carry contacts 26 and 27 so connected by conductors 28, 29 and 30 through battery 31 as to make and break current through an electromagnet 32 of an operating mechanism which may be a solenoid or an electromagnet. 30

The contact mechanism need not be of the 35 same form as that shown, though the type illustrated excellently carries out one desirable feature of giving a quick make and quick break to avoid partial contact. This prevents arcing across the contacts. 40

As the ratchets turn in counter-clockwise direction finger 24 snaps from each individual cam 22' in turn to make a quick and complete engagement between contacts 26 and 27 and this engagement remains undisturbed by the lifting 45 of finger 25 upon the successive cam 22', to quickly and completely break the engagement between the contacts 26 and 27 when the finger 25 drops from the cam surface 23'. 40

The ratchet 22 is rigidly attached to the shaft 50 and the ratchet 23 frictionally engages the ratchet 22, so that the angular relation between the two ratchets may be adjusted by loosening an engaging nut.

The electromagnetic device shown in Figure 1 55

is solenoidal but, as to my broad invention, is intended to be emblematic merely of any electromagnetic device capable of serving the purpose.

The contact-carrying strips 24 and 25 not only make the contacts but both act as stops to prevent reverse movement of the ratchet mechanism by which they are operated. Some stop mechanism is needed to prevent reversal. It is a part of the meter system and may be secured directly to any of the meter spindles which can conveniently be extended and which has a slow enough movement for the purpose or which, even outside of the meter is geared down for that use.

The solenoidal core 33 in Figure 1 is coupled through a joint 34 and pivots 35 with a plurality of ratchet-carrying strips 36 each of whose latches 37 is adapted to engage with the ratchets 38 upon one of a plurality of ratchet wheels 38 upon a shaft 39. The several latches and ratchets are so placed that the latches will engage at different parts of the angular positions of the shaft 39 and in this manner the distance between successive teeth is divided up and one or other of the latches is made effective to engage its ratchet teeth and to correspondingly turn the shaft during the movement of the engaging pawl. This may be accomplished by shifting either the latches or the ratchets progressively, giving an improved latching sensitiveness proportional to the number of ratchet wheels used. A holding pawl 40 is applied to each ratchet wheel 38.

The levers 36 are pivoted about any suitable shaft 39 and all lift and lower together when the solenoidal core 33 is lifted and is allowed to lower.

The levers 36 are fastened together beyond the latches by any suitable means such as bolt 41.

The shaft 39 in this form is connected by any suitable gearing with mechanism by which the feeding of treating solid or liquid material is effected or is controlled. Mechanism for this purpose—as for the train of operation already described—is shown and will be explained because of the statutory requirement. However, other mechanism for the purpose is later described in order to suggest that the mechanism of Figure 1 is one form only of many forms (of which, necessarily, space permits showing of but few) by which my invention may be carried out.

Without intending to restrict the invention by the earlier description nor by that to follow the mechanism shown will be explained.

The shaft 39 carries a pinion 42 which engages a gear 43 upon the same shaft 44 as a pinion 45 which operates a gear 46. This gear is mounted upon shaft 47 which is shown as carrying a sprocket wheel 48 by which a belt, sprocket chain 49 or other operating mechanism is moved; with the effect that both rotarial movement from any of the shafts and straight line movement from the belt or chain are available for effecting any feeding movement desired, of which several examples are hereinafter described.

As the connection between rotarial or straight line movement and the different feeds will be obvious I have not attempted to show the connection with this operating mechanism in all of the figures.

The several shafts and other mechanisms described are shown as supported by side frame plates 50 and 51, but these as well as the number and arrangement of any shafts used and the particular connections by which the electromagnetic impulses are integrated may be greatly

varied and are varied in other constructions shown.

The extent of stroke of the solenoidal core or armature determines in a solenoidal form the amount of feed for each impulse given and this is regulated in this first illustration as best seen in Figure 3.

A shaft 52 is pivoted in any frame member 53 so that it can be turned by a hand wheel 54 to rotate a thread 52' upon the shaft. The thread carries a block 56 which is retained against rotation in any suitable way and whose height limits the downward movement of the core or armature and thus determines the amount of travel. The height of the block is shown by an outside indicator, not shown, through a worm 57 on shaft 52 and a worm wheel 57' on a shaft suitably mounted. The shaft may operate any kind of a pointer or indicator to show the height of the block. 20

In view of my invention and disclosure variations and modifications to meet individual whim or particular need will doubtless become evident to others skilled in the art to obtain all or part of the benefits of my invention without copying 25 the structure shown, and I, therefore, claim all such in so far as they fall within the reasonable spirit and scope of my invention.

Having thus described my invention, what I claim as new and desire to secure by Letters Pat- 30 ent is:—

1. In a feeding mechanism for proportional addition of treating material to a liquid, an electric circuit, a source of energy therefor, a contact device in the circuit opening and closing the circuit at intervals, an electromagnet in the circuit, an armature therefor, a plurality of pivoted links connected with said armature to swing with its movement, pawls carried by said links, ratchet wheels with which the pawls engage, the several 40 pawls and their ratchet wheels being staggered, a shaft to which the ratchet wheels are all secured, a gear mounted on said shaft and feed-operating mechanism driven by said gear whereby the treating material is fed to the liquid. 45

2. In a feeding mechanism for proportional addition of treating material to a liquid, an electric circuit, a source of energy therefor, a contact device in the circuit opening and closing the circuit at intervals, an electromagnet in the circuit, 50 an armature therefor, a plurality of pivoted links connected with said armature to swing with its movement, pawls carried by said links, ratchet wheels with which the pawls engage, the several pawls and their ratchet wheels being staggered, 55 a shaft to which the ratchet wheels are all secured, a gear mounted on said shaft, feed-operating mechanism driven by said gear for delivery of the treating material to the liquid and an adjustable stop for the throw of the armature to 60 vary the rate at which the material is fed.

3. In an electromagnetic feeding mechanism, a pair of spring contacts having engaging surfaces adapted to come together, a cam surface adapted to engage one of the spring strips to lift 65 it away from the other and to allow it to snap against the other when released from the cam surface and a cam adapted to rotate with the first-named cam to engage the second of said strips to leave the second strip in position to be 70 engaged by the first strip when released and to snap free from engagement with the first strip when the second strip is released by the second cam surface and an electric circuit closed by engagement of the strips. 75

4. A step-by-step electromagnetic feeding mechanism, in combination with a quick opening and quick closing snap switch therefor, comprising first and second cams, first and second spring strips engaged thereby successively, contact members carried by the strip adapted to engage in certain positions of the strip, the first strip being

lifted free from contact engagement by the first cam and snapping into engagement when freed therefrom and the second strip being lifted with the first strip by the second cam during contact and snapped free from contact engagement with the first strip when released by the second cam. 5
